UNITED STATES PATENT OFFICE.

JOHN W. ORROCK, OF WESTMOUNT, QUEBEC, CANADA.

UNDERGROUND CONDUIT.

Application filed January 19, 1921. Serial No. 438,488.

To all whom it may concern:

Be it known that I, JOHN WILSON ORROCK, of the city of Westmount, in the Province of Quebec, Canada, have invented certain new and useful Improvements in Underground Conduits; and I do hereby declare that the following is a full, clear, and exact description of the same.

My invention relates particularly to underground conduits of the type illustrated in United States Patent No. 1,155,610 granted on the fifth day of October, 1915, to John Wilson Orrock and Henry H. Vaughan.

The invention has for its object to provide a design of conduit of this type in which the relatively weak top of the draining member, the latter being termed an invert in the earlier patent, is relieved of the weight of the half-round pipe or arch member. A further object of the invention is to prevent seepage water which percolates to the top of the arch member from finding its way along the same, the idea being to cause it to drain laterally. It may be explained that the underground conduit developed by me has for its underlying essential idea a drainage member or tile for supporting steam pipes or the like and coating with the arch section in forming a housing for these steam pipes and the like. The edges of the arch section are arranged in such relation with the tile that any water appearing on or in the conduit will be drained away. My present invention is a further development of this idea and its object generally speaking is, as with my former invention, to utilize wherever possible standard materials.

In order to relieve the drainage tile of the weight of the arch section while still maintaining the drainage and housing properties of the patented conduit, I form the arch section slightly wider than the drainage tile over which it arches and it is supported either upon the same floor as the tile or upon the edges of the latter which under such conditions are specially formed for the purpose as mentioned hereinafter.

This arch section consists of corrugated metal which has the dual function of supporting a load with relatively light material, and at the same time presenting lateral surface drains which break the flow of water along the top of the arch section and cause it to fall laterally. Another function of the corrugations is that they have effective bonding properties in connection with the outer

coating of concrete when such is used, thereby particularly adapting this arch section for use as the arch member of an underground conduit for pipes in the transmission of steam for heating and power purposes.

In the laying of my improved underground conduit it is sometimes possible to excavate so as to present a floor sufficiently hard to permit the drainage tile to be seated thereon and the edges of the arch sections also to rest thereon, but when the nature of the floor is such that it will not support the edges of the arched section the latter may be provided with means for supporting it on the side edges of the drainage tiles.

For small installation, where the pipes are not large, the drainage base and its cover may be both of tile and rest on a floor formed by the ground or on a concrete base as conditions may require; and if necessary, as a further protection the conduit thus formed may be covered with concrete. It is also preferable in each case to have the drainage base the full width of the conduit and of sufficient strength to provide bearing for supporting itself and the comparatively heavy insulated conductors such as steam pipes, electric cables, water pipes and other conductors.

My improved conduit is well adapted for any form of underground conductor requiring protection and it has the virtue of simplicity of construction, protection against wetness reaching the insulation or lagging of heat conductors, and, which is of considerable importance, the conductors within it are accessible for inspection, repairs and renewal.

For full comprehension, however, of my invention reference must be had to the accompanying drawings in which similar reference characters indicate the same parts and wherein:

Figure 1 is a transverse sectional view of my improved conduit in its proper location beneath a road bed;

Figure 2 is a side elevation of my improved conduit partly in vertical sectional view, the section being taken on line 2-2 Fig. 1;

Figure 3 is a detail view of one of the arch sections removed;

Figure 4 is a detail view of the drainage tile.

My underground conduit is designed particularly for conducting insulated steam pipes and the like, such as indicated at b

and *c*. The drainage member I recommend is a flat sided and flat ended concrete member or tile *d* having longitudinal drainage passages *d*¹ as shown in Figures 1, 2 and 4; and the arch section consists of iron transversely corrugated as indicated at *e*. When a soft soil is encountered, a floor of concrete or other relatively hard material is first laid, and arch sections having sides of sufficient length to extend as at *e*¹, to rest on the concrete floor at each side of the drainage tile are provided. A conduit of this form is shown in Figures 1 and 2.

In order to prevent lateral displacement of the drainage tiles their bottoms are provided with ribs *k* which bite into the ground.

In all cases where a concrete covering is used the points of contact, *m*, with the bottom of the trench or a concrete floor are provided with tenons *n* supplemented with dowels *o*.

The roller bearing indicated at *b*²⁰ in Figures 1 and 2, upon which the conductor *b* is supported to accommodate expansion and contraction of the pipe, is and may be of any usual and preferred construction.

What I claim is as follows:

1. A conduit for the purpose described, comprising a drainage tile and a transversely corrugated metal arch section arched over the drainage tile, the said tile being throughout its length of less width than the arch section.

2. In an underground conduit for a conductor with means for supporting the conductor, the combination with a drainage tile located entirely below the conductor supporting means, of an arch section adapted to have its edges extend below the top edges of the drainage tile and means for supporting the arch section relatively to the said drainage tile.

3. In an underground conduit the combination with a floor, of a concrete drainage tile extending throughout the length of the conduit adapted to support a conductor, such tile resting upon the floor, and an arch section forming with the drainage tile a conduit for the said conductor, the said arch section resting upon and being supported by the floor with the tile within it.

4. In an underground conduit the combination with a floor, of a concrete drainage base adapted to support a conductor, such base resting upon the floor, and an arch section forming with the drainage tile a conduit for the said conductor, the said arch section resting upon and being supported by the floor, and a concrete cover for the complete conduit resting on the floor.

5. In an underground conduit the combination with a floor, of a concrete drainage tile adapted to support a conductor,

such tile resting upon the floor, and an arch section forming with the drainage tile a conduit for the said conductor, the said arch section resting upon and being supported by the floor, and a concrete cover for the complete conduit resting on the floor and means preventing relative lateral displacement of the contacting faces of the cover and floor.

6. In an underground conduit the combination with a floor, of a concrete drainage tile adapted to support a conductor, such tile resting upon the floor, and an arch section forming with the drainage tile a conduit for the said conductor, the said arch section resting upon and being supported by the floor, and a concrete cover for the complete conduit resting on the floor, the contacting faces of the cover and floor being tenoned.

7. In an underground conduit the combination with a drainage tile, of a metal arch section adapted to have its edges extend below the top edges of the drainage tile and means for supporting the arch section relatively to the said drainage tile.

8. In an underground conduit the combination with a drainage tile, of a corrugated galvanized iron arch section adapted to have its edges extend below the top edges of the drainage tile and means for supporting the arch section relatively to the said drainage tile.

9. In an underground conduit the combination with a drainage tile, of a corrugated galvanized iron arch section adapted to have its edges extend below the top edges of the drainage tile and means for supporting the arch section relatively to the said drainage tile, and a concrete cover for the conduit thus formed.

10. In an underground conduit the combination with a floor, of a concrete drainage tile adapted to support a conductor, such tile resting upon the floor, and a corrugated galvanized iron arch section forming with the drainage tile a conduit for the said conductor, the said arch section resting upon and being supported by the floor and a concrete cover for the conduit thus formed.

11. In an underground conduit for a heat conductor, the combination with a floor of relatively hard material, of a tile having drainage ducts extending longitudinally throughout, a corrugated metal arch section with substantial flat sides arched over the tile with the sides of the arch straddling the tile and resting upon and supported by the floor and completely housing the said tile.

12. A conduit comprising in combination, a floor, a tile resting on the floor and having longitudinal drainage ducts extending therethrough, said tile being constructed and arranged to support conductors, an arch sec-

tion arched over the tile with the sides of the arch straddling the tile and completely housing the same and having transverse surface drains adapted to break the flow of water along the top thereof and causing it to fall laterally to the floor.

13. In an underground conduit the combination with a floor, of a concrete drainage tile extending throughout the length of the conduit and adapted to support a conductor, such tile resting upon the floor, and an arched section forming with the drainage tile a conduit for the said conductor, the said arched section resting upon and being supported by the floor with the drainage tile within it.

14. In an underground conduit the com-

bination with a floor, of a concrete drainage tile extending throughout the length of the conduit and adapted to support a conductor, such tile resting upon the floor, and an arch section forming with the drainage tile a conduit for the said conductor, the said arch section resting upon and being supported by the floor, and means mounted upon the top of the tile within the arch section for supporting a steam pipe or the like.

In testimony whereof I have signed my name to this specification in the presence of two witnesses.

JOHN W. ORROCK.
